UNITED STATES PATENT OFFICE.

WILLIAM F. GROENE, OF CINCINNATI, OHIO, ASSIGNOR TO THE R. K. LE BLOND MACHINE TOOL COMPANY, OF CINCINNATI, OHIO, A CORPORATION OF DELAWARE.

TAPER ATTACHMENT FOR LATHES.

Application filed May 20, 1921. Serial No. 471,031.

To all whom it may concern:

Be it known that I, WILLIAM F. GROENE, a citizen of the United States, residing at Cincinnati, county of Hamilton and State of Ohio, have invented an Improvement in Taper Attachments for Lathes, of which the following description, in connection with the accompanying drawings, is a specification, like characters, on the drawings representing like parts.

This invention relates to taper attachments for lathes whereby the lathe tool may be moved either toward or from the centre of the lathe while at the same time it is moved toward an end of the lathe at a speed bearing a predetermined relation to its first-mentioned movement.

Taper attachments for lathes are used only when it is desired to perform certain operations, and it is therefore desirable to construct the taper attachment so that the lathe tool may be easily and quickly placed under the control of the same, and likewise may be easily and quickly released from the taper attachment and the parts restored to their normal operating condition.

In taper attachments for lathes, it is customary to provide a taper rail which may be adjusted to different angles, and to provide a shoe having sliding engagement with the rail, the arrangement being such that as the shoe is slid along the inclined rail, it will move either toward or from the longitudinal axis of the lathe, and by suitable connections, this movement of the shoe is imparted to the lathe tool. These sliding shoes usually fit tightly upon the rail to prevent play from occurring therebetween, and if the bearing surfaces of the shoe and taper rail become dry or dirty, considerable force is required to slide the shoe along the rail.

An important feature of the present invention, therefore, consists in a taper attachment which is so constructed that the cross-feed screw is entirely relieved from lateral bending forces throughout the movement of the shoe along the taper rail, and in which the cross-feed screw is also relieved from longitudinal stresses during the use of the taper mechanism.

Another feature of the invention consists

in taper mechanism which is so constructed that the cutting tool may be easily and quickly placed under the control of the mechanism, and released therefrom.

Still another feature of the invention consists in mechanism which provides a firmer and more direct connection between the sliding shoe and compound rest or cross-slide than has been provided heretofore.

The accompanying drawings illustrate a good, practical form of the invention, the details of which may be modified within the true scope thereof, as defined by the claims.

In the drawings:

Figure 1 is a vertical transverse sectional view taken through the lathe bed and its carriage;

Fig. 2 is an enlarged plan view of the taper attachment and a portion of the lathe;

Fig. 3 is a sectional view taken on the line 3—3 of Fig. 2; and

Fig. 4 is a side view of the taper attachment looking to the right with respect to Fig. 2.

In the drawings: 10 designates the lathe bed having the carriage 11 slidably mounted thereupon; and mounted upon the carriage is the cross-slide 12 which supports the tool-carrying mechanism 13. The construction of these parts forms no part of the present invention, and they may be given the usual or any preferred embodiment.

In the present embodiment of the invention, a bracket 14 is rigidly secured to the rear face of the carriage 11 by suitable means such as bolts 15. The bracket 14 may serve to slidably support the bar 16 having the dove-tailed bearing surfaces 17, and upon the upper face of the bar 16 is pivotally mounted the taper guide rail 18 pivotally secured to the bar 16 by the pin 19. Upon the guide-rail 18 is slidably mounted the shoe 20 preferably having a tapered spline 21 for taking up wear between the shoe and rail, and the bracket 14 may likewise be provided with a spline 22 engaging the bar 16.

As above pointed out, an important feature of the present invention consists in a construction in which the cross-feed screw is relieved from both lateral and longitudinal stresses while the taper attachment is in use,

and satisfactory means to this end will now be described.

The compound rest or cross-slide 12 is provided with the cross-feed screw 23 which 5 serves to move the slide 12 upon the carriage crosswise of the lathe, and the screw 23 is operatively secured to the slide by the nut 24 rigidly secured to the slide by any suitable means such as a boss 25 and nut 26. The 10 rear portion of the screw 23 is journaled in a relatively long sleeve 27, and the screw is prevented from moving longitudinally within the sleeve in one direction by the shoulder 28 upon the screw and the thrust bearing 29, while the screw is prevented from 15 moving in the opposite direction relative to the sleeve by the thrust bearing 30 and nuts 31.

The sleeve 27 in the embodiment shown is 20 provided with an enlarged ring-like portion 32 and oppositely projecting end portions 33, as best shown in Fig. 4. The end portions 33 are slidably mounted in spaced bearings or guideways 34, the construction being 25 such that the sleeve 27 is supported for sliding movement transversely of the lathe.

When the cross-feed screw 23 is rotated to feed the cross-slide 12 in either direction the 30 tendency of the screw to move in the direction of its length is resisted by the sleeve 27. It is therefore important to provide means for firmly holding the sleeve from being moved by the screw, and to this end, in the 35 embodiment shown, the shoe 20 has a boss 35 extending upwardly therefrom, which is journaled in the ring-like portion 32 of the sleeve. By this construction the sleeve 27 is firmly connected to the shoe 20 while relative rotation between the shoe and sleeve is 40 permitted, and the sleeve is positioned in close proximity to the shoe, which desirably increases the rigidity of the connection therebetween.

In the embodiment of the invention illustrated, the bar 16 is provided at one end 45 with a strap 36 secured thereto by a bolt 37, and the other end of the strap is secured at 38 to a clamp 39 adapted to be secured to the lathe bed as at 40 by operating the bolt 41 to tighten the jaw 42 of the clamp (see Fig. 4). When it is desired to use the taper attachment, the clamp 39 is secured to the lathe bed as shown in Figs. 2 and 4, then the shoe 20 will be slid along the taper guide-rail 18 as the carriage 11 is moved toward or from 55 the lathe head. Movement of the carriage 11 along the lathe bed is imparted to the shoe 20 by the sleeve 27, and since the ends of this sleeve are supported by the guide-ways 34, it will be seen that the sleeve is well 60 adapted to withstand the stresses to which it may be subjected in imparting movement to the shoe.

It is desirable to provide means for rigidly connecting the cross-slide to the shoe 65

20, when the taper attachment is in use, and after the screw 23 has been rotated to adjust the cross-slide. To this end, in the embodiment shown, a slotted bar 43 is provided, one end of which is firmly secured to the cross-slide 12 by a pin 44 and bolt 45. The slot 46 of the bar 43 is adapted to slidably receive the clamping bolt 47 having threaded engagement with the boss 35 of the shoe. The arrangement is such that the bar 75 43 may be firmly clamped against the upper face of the portion 32 of the sleeve by tightening the bolt 47 to force the clamp 48 against the upper face of the bar 43, whereupon the shoe 20 and bar 43 will be rigidly 80 clamped to the sleeve 27. And when the parts are in this position, the movement of the shoe toward or from the longitudinal axis of the lathe will be imparted to the cross-slide 12 through the bar 43.

The forward end 49 of the cross-feed screw 23 is slidably received in a sleeve 50 and is secured thereto by a key 51. The sleeve 50 may be rotated by the handle 52, and this movement is imparted to the screw 23 by 90 the key 51, the construction being such that the screw is free to slide in the sleeve 50, when movement is imparted thereto in the direction of its length.

From the foregoing description it will be 95 apparent that the screw 23 is relieved from longitudinal stresses during the use of the taper mechanism by tightening up the clamping bolt 47; and it will also be apparent that since the sleeve 27 serves to slide the shoe 100 along the guide-rail, the screw 23 is also relieved from lateral stresses. Furthermore, by securing the sleeve 27 to both the cross-feed screw and the sliding shoe, a compact, strong, and durable construction is obtained. 105

Various means might be provided for adjusting the taper rail 18 about the pivot pin 19 to the desired angle, and one means to this end consists in providing the rail 18 with a pinion 53 positioned to mesh with 110 the rack 54 secured to the bar 16, so that when the pinion is rotated it will travel along the rack and impart angular movement to the taper-rail. In the embodiment shown, the pinion 53 is rigidly secured to the 115 upwardly-extending shaft 55 mounted to rotate in a sleeve 56 mounted upon the rail 18, and at the upper end of the shaft 55 is provided a knurled wheel 57 adapted to rotate the shaft 55 and pinion 53. After the 120 knurled wheel 57 has been rotated to adjust the taper-rail 18 to the desired position, the rail may be clamped in its position of adjustment by tightening the nuts upon the bolts 58.

In the embodiment shown, the boss 35 of the sliding shoe has a hole 59 formed therethrough, through which the cross-feed screw 23 freely extends, and since the shoe is turned relative to the screw 23 when the 130

guide-rail 18 is moved to different angles, the hole 59 is flared outward toward its ends to form sufficient clearance for the screw.

From the foregoing description when read 5 in connection with the drawings, it will be seen that the cross-feed screw 23 is at all times connected to the sliding shoe 20 by the sleeve 27, and that when it is desired to use the taper attachment all that is necessary is 10 to secure the clamp 39 to the lathe bed and to tighten the clamping bolt 47. When it is no longer desired to use the taper attachment, all that is necessary is to release the clamping bolt 47 and the clamp 39.

15 What is claimed is:—

Claims:

1. In a taper attachment for lathes, the combination of a lathe carriage having a cross slide mounted thereupon and a guide-way at the rear side of the carriage, a bracket secured to the carriage at the rear side thereof and having a guide-way, a taper rail having a shoe slidably mounted thereupon, a cross-feed screw connected to the 25 cross-slide and extending across said shoe, a long sleeve having its ends slidably mounted in said guide-ways and having the rear portion of the screw journaled therein, and means for pivotally securing the sleeve 30 to the shoe.

2. In a taper attachment for lathes, the combination of a lathe-carriage having a cross-slide mounted thereupon, a bracket secured to said carriage and having a guide-way extending transversely of the lathe, a taper rail, a sliding shoe upon the rail and positioned between said guide-way and the front of the lathe, a sleeve secured to said shoe and slidably mounted in said guide-way, and a cross-feed screw connected to the cross-slide and having an end journaled in said sleeve and held from movement bodily relative to the sleeve.

3. In a taper attachment for lathes, the combination of a lathe-carriage having a cross-slide mounted thereupon, a bracket secured to said carriage and having a guide-way extending transversely of the lathe, a taper rail, a sliding shoe upon the rail and having a projecting boss, a sleeve slidably mounted in said guide-way and adapted to pivotally receive said boss, and a cross-feed screw connected to the cross-slide and having an end journaled in said sleeve and held from movement longitudinally in the sleeve.

4. In a taper attachment for lathes, the combination of a lathe-carriage having a cross-slide mounted thereupon, a cross-feed screw connected to the cross-slide, spaced 60 guide-ways disposed transversely of the lathe at the rear side thereof, a bracket secured to said carriage and supporting the outer guide-way, a taper rail, a sliding shoe upon the rail and having a boss extending 65 therefrom, a screw-engaging slide slidably

mounted in said guide-ways and adapted to pivotally receive said boss, and means for rotatably securing the cross-feed screw to said screw-engaging slide in axial alignment therewith.

5. In a taper attachment for lathes, the combination of a lathe-carriage having a cross-slide mounted thereupon, a cross-feed screw connected to the cross-slide, a bracket secured to said carriage at the rear side 70 thereof and having a guide-way, a taper rail, a sliding shoe upon said rail, a screw-engaging slide connected to the cross-feed screw and slidably mounted in said guide-way, a bar secured to said cross-slide, and 75 means for simultaneously clamping the screw-engaging slide and the bar to said shoe.

6. In a taper attachment for lathes, the combination of a lathe-carriage having a cross-slide mounted thereupon, a bracket secured to said carriage and having a guide-way extending transversely of the lathe, a taper rail having a sliding shoe mounted thereupon, a sleeve slidably mounted in said 80 guide-way, a cross-feed screw connected to said cross-slide and to the sleeve, a boss upon the shoe extending into said sleeve, a bar secured to the cross-slide, and means cooperating with said boss to simultaneously clamp 85 said sleeve and bar to the sliding shoe.

7. In a taper attachment for lathes, the combination of a lathe-carriage having a cross-slide mounted thereupon, a bracket secured to said carriage and having a guide-way, a taper rail having a sliding shoe mounted thereupon, a long sleeve slidably mounted in said guide-way and extending across said shoe, a cross-feed screw connected to said cross-slide and having an end 100 extending through said sleeve and journaled therein, and means engaging the sleeve and shoe to pivotally connect them.

8. In a taper attachment for lathes, the combination of a lathe-carriage having a cross-slide mounted thereupon, a bracket secured to said carriage and having a guide-way, a sleeve slidably mounted in said 110 guide-way, a taper rail, a shoe slidably mounted on the taper rail and having a boss 115 projecting into the sleeve to form a pivotal connection therebetween, and a cross-feed screw connected to the cross-slide and having an end extending through said boss and sleeve and journaled in the latter.

9. In a taper attachment for lathes, the combination of a lathe-carriage having a cross-slide mounted thereupon, a bracket secured to said carriage and having a guide-way, a sleeve slidably mounted in said 125 guide-way, a taper rail, a shoe slidably mounted on the taper rail and having a boss projecting into the sleeve to form a pivotal connection therebetween, a cross-feed screw connected to the cross-slide and having an 130

end journaled in said sleeve, a bar secured to said cross-slide, and means for clamping said bar to said boss.

10. In a taper attachment for lathes, the combination of a lathe carriage having a cross-slide mounted thereupon, a taper rail having a shoe slidably mounted thereupon, a cross-feed screw connected to the cross-slide,

a sleeve mounted upon said shoe and having an end of the cross-feed screw journaled 10 therein, and a guide for the sleeve having an end of the latter slidably mounted in the guide.

In testimony whereof, I have signed my name to this specification.

WILLIAM F. GROENE.
